UNITED STATES PATENT OFFICE.

CHARLES VALENTINE SZCZYGIEL, OF AMSTERDAM, NEW YORK.

WINDOW-VENTILATOR.

No. 904,100.

Specification of Letters Patent.

Patented Nov. 17, 1908.

Application filed August 24, 1908. Serial No. 450,000.

To all whom it may concern:

Be it known that I, CHARLES VALENTINE SZCZYGIEL, a citizen of the United States, residing at Amsterdam, county of Montgomery and State of New York, have invented 5 certain new and useful Improvements in Window-Ventilators, of which the following is a specification.

The invention relates to such improvements and consists of the novel construction 10 and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a plan view of my improved ventilator. Fig. 2 is a vertical 20 section taken on the broken line 2—2 in Fig. 1. Fig. 3 is a similar section taken on the broken line 3—3 in Fig. 1.

The ventilator comprises a triangular plate, 1, preferably of perforate sheet-metal, 25 an open triangular sheet-metal frame, 2, secured to the perforate plate by means of the bolts, 3, and nuts, 4, an open triangular bearing-plate, 5, of sheet-material, a little thicker than the thickness of ordinary window glass, interposed between the frame and perforate plate. This bearing-plate is given 30 approximately the same form as the triangular frame to form a seat, 6, for a cover, 7, which cover is hinged to the frame by one or 35 more hinges, 8, and adapted to swing to and from its seat to open and close the perforate portion of the triangular perforate plate. The cover is provided with a thumb-latch, 9, adapted to lock the cover in a closed position, as seen in Figs. 1 and 3. The cover is 40 shown closed and locked in Fig. 1, with the lower part broken away to show a portion of the perforate plate.

The outlines of the triangular frame are 45 similar to those of the perforate plate with each of its sides slightly shorter than the corresponding sides of such plate, so that when the frame is superposed upon the perforate plate and secured thereto the edges, 50 10 and 12, of the perforate plate project beyond the corresponding edges of the triangular frame, and are adapted to rest upon the window-sash at one corner of a window pane, and be secured to the sash in any 55 known manner, as by means of putty ap-

plied to the sash in the same way it is applied to secure the glass.

The ventilator may be inserted in a sash already glazed, by removing a pane of glass, and cutting therefrom one corner. 60

When the side of the ventilator opposite the right angle, 11, is curved to form the arc of a circle, having its center at such right angle, the glass is similarly cut, so that the glass will enter the space or groove, 17, located between the perforate plate and the triangular frame, and its curved edge will bear against the inclosed triangular sheet-material, 5, which is preferably of a yielding nature, as rubber or vulcanized fiber. 65 70 75

As a means for providing a small ventilator opening when the cover is closed upon the perforate portion of the perforate plate, or for introducing fresh air through a hose to different parts of the room containing 75 such window ventilator, I make use of a nipple, 14, inserted through one corner of the triangular frame as shown.

The nipple may extend to a perforated portion of the perforate plate, or it may extend entirely through the perforate plate, 80 as shown in Fig. 3, in which case the nipple is provided with a screen, 15. When it is desired to take the air to some particular part of the room, the end of a common hose 85 may be slid on the inner projecting end of the nipple. When the hose is not applied, the nipple may, when desired, be closed in any known manner as by any ordinary cap placed thereon. 90

In Fig. 3, the projecting end of the nipple is shown closed by a cap, 18. I have also indicated in such figure, by dotted lines, one end of a hose, 16, attached to such nipple, the other end of the hose being broken away. 95

What I claim as new and desire to secure by Letters Patent is—

1. In a window ventilator, the combination with the triangular perforate plate; of a triangular open frame; a triangular open bearing-plate interposed between the frame and perforate plate with its inner edges on two sides, projecting inwardly of the frame; means for securing the frame, interposed plate and perforate plate together; and a 100 cover approximately fitting the opening in the frame and hinged to one side of the frame, whereby the cover is adapted to swing into and out of such opening. 105

2. In a window ventilator, the combina- 110

tion with the triangular perforate plate; of a triangular open frame; a triangular open bearing-plate interposed between the frame and perforate plate with its outer edge, on one side, withdrawn from the corresponding edges of the frame and perforate plate to form a pane-receiving groove between the frame and perforate plate; means for securing the frame and plates together; and means for opening and closing the opening in the frame.

3. In a window ventilator, the combination with a triangular perforate plate having two of its sides extending at right angles to each other; of a similarly outlined open frame having its three sides slightly shorter than the corresponding sides of the perforate plate; means for securing the frame and plate, together with their sides, opposite the right angles of the frame and plate, in alinement with each other and the other two sides of the frame located inwardly of

the corresponding sides of the perforate plate, with a glass-receiving groove between the alined edges of the frame and plate; and means for opening and closing the opening in the frame.

4. In a window ventilator, the combination with a triangular perforate plate; of a similarly outlined open frame; means for securing the frame and plate together; means for opening and closing the opening in the frame leading to the perforations in the perforate plate; a screened nipple inserted in one corner of the frame, and providing a passage-way through the frame and perforate plate; and independent means for closing the nipple.

In testimony whereof, I have hereunto set my hand this 18th day of August, 1908.

CHARLES VALENTINE SZCZYGIEL.
